UNITED STATES PATENT OFFICE.

JAMES S. THOMPSON, OF PELHAM, NEW YORK.

BRAKE-SHOE MOLD.

Application filed August 1, 1923. Serial No. 655,066.

To all whom it may concern:

Be it known that I, JAMES S. THOMPSON, a citizen of the United States, residing at Pelham, in the county of Westchester and 5 State of New York, have invented certain new and useful Improvements in Brake-Shoe Molds, of which the following is a specification.

This invention relates to the manufacture 10 of brake shoes and more particularly to the mold in which the shoe is cast, and its object is broadly to enable a brake shoe to be cast in a permanent mold, as well as it can be cast in a sand mold, and with an 15 additional advantage of reduction in time and cost.

Another object of the invention is to provide a simple means for supporting in the mold the core which is employed for forming 20 the opening in the attaching lug of the shoe.

And another object of the invention is to enable a unit comprising an assembly of the lug, the core therefor and the reinforcing back to be easily and quickly inserted in the 25 mold.

Other objects of my invention will become apparent as the detail description progresses, reference being had to the accompanying 30 drawings which illustrate a selected embodiment of the invention, and wherein—

Fig. 1 is a central transverse section taken through the mold.

Fig. 2 is a central longitudinal section through the mold taken on line 2—2 of 35 Fig. 1.

Fig. 3 is a horizontal section taken on line 3—3 of Fig. 2.

Figs. 4 and 5 are perspective views of 40 certain refractory sections forming parts of the mold, and

Fig. 6 is a perspective view of the steel reinforcing back, attaching lug and the core for forming the opening through the attaching lug, the several parts being assembled as 45 a unit.

Referring to the drawings, the mold comprises a metal drag 10 and a metal cope having two members 11 and 12. A suitable mold cavity for making the desired casting 50 is provided in the mold, partly in the drag and partly in the cope. The cope members have side lugs 14, and pivot rods 15 engage these lugs and corresponding lugs on the drag for pivotally connecting the cope mem-

bers to the drag. A pair of clamps 17 may 55 be provided for securing the cope members in closed position and the pouring gate 18 may be arranged as shown to register with an opening in the reinforcing back 19, which is embedded in the brake shoe casting. The 60 lug 20 and the sand core 21 therefor are preferably assembled as a unit with the reinforcing back 19 and secured together by means of the wire ties 22 so that these parts may be easily handled and inserted as a unit 65 in the mold for the casting operation. The parting line between the two members of the cope is offset to provide a projection 23 upon the member 11 and a complementary recess 24 in the member 12, and this construction 70 is provided so that the aforesaid unit can be inserted in one member of the cope and both members of the cope swung to closed position without damaging or disarranging the unit or any part thereof. A recess 75 25 formed in the projection 23 is adapted to receive the sand core 21 and it is provided with inclined end surfaces 26 adapted to engage inclined end surfaces 27 of the sand core so that when the sand core is inserted 80 in the recess 25 from the parting line surface of the projection 23, the core will be held against displacement in a direction toward the mold cavity 13. The recess 25 is preferably designed to receive the entire 85 sand core 21 and for that reason it is preferably of a depth substantially equal to the width of the core. It will be noted that the recess 25 is formed in a refractory section 28 forming part of the cope member 11. 90 It will also be noted that the cope member 12 is provided with a refractory section 29 and that the drag member 10 is provided with a refractory section 30. These refractory sections are provided to protect the hot metal from the chilling effect of the metal of the mold.

When the mold is to be prepared for the casting operation, the operator first brings the cope members 11 and 12 into the positions shown by dotted lines in Fig. 1. The reinforcing back 19, the attaching lug 20, and the sand core 21 may then be placed in the cope member 11 as a unit. The entire sand core 21 will be received within the recess 25 and the attaching lug and steel back will be properly positioned in that portion of the mold cavity which is formed in 100 105

the cope member 11. The cope members are then closed and secured by the clamp 17. The inclined surfaces 27 of the core 21 will engage the inclined surfaces 26 of the recess 5 and prevent the core from falling into the mold cavity. The steel back and the attaching lug will, of course, be supported in proper position by the core. As the core is received in its entirety within the recess 10 25 in cope member 11, it can not be injured by the latter when the cope member 12 is brought to the closed position. In addition to permitting the mold to be closed without disarranging the parts to be embedded in the 15 shoe casting my invention permits the mold to be opened for removal of the shoe casting without injury to any part of the mold. After the cope members have been brought to their closed position and secured therein 20 by means of the clamps 17, the mold is ready for the casting operation, a plurality of sand vents 32 being provided in the cope members to permit gases to escape from the mold cavity during the casting operation.

25 As hereinbefore set forth, the drag member 10 and the cope members 11 and 12 are provided with refractory sections which are adapted to protect the hot metal introduced into the mold from the chilling effect of the 30 metal of the mold. The refractory sections 28, 29 and 30 form substantially all of each of the walls of the mold cavity 18, thus enabling the mold to produce a brake shoe of substantially uniform texture. However, in 35 the event that brake shoes were desired having integral composite wearing faces, the refractory sections could be modified so as to allow the metal of the mold to chill the end portions of the shoe casting.

40 I am aware that changes in the form, construction and arrangement of parts may be made without departing from the spirit and without sacrificing the advantage of the invention and I consider myself entitled to 45 make all such changes as fairly fall within the scope of the following claims.

I claim—

50 1. The combination with a core for forming the opening in the attaching lug of a brake shoe, of a permanent mold for casting the brake shoe and comprising a drag and a two-member cope having a mold cavity therein, each of said cope members having a part of the mold cavity therein, and one of said cope members having a recess adapted to receive the entire core.

60 2. The combination with a core for forming the opening in the attaching lug of a brake shoe, of a permanent mold for casting the brake shoe and comprising a drag and a two-member cope having a mold cavity therein, each of said cope members having a part of the mold cavity therein and one of said cope members having a recess shaped to engage and to hold the core in

place, the recess being adapted to receive the entire core.

3. The combination with a core for forming the opening in the attaching lug of a brake shoe, of a permanent mold for casting the brake shoe and comprising a drag and a two-member cope having a mold cavity therein, each of said cope members having a part of the mold cavity therein and one of said cope members having a recess adapted to receive the core, the recess being of a depth substantially equal to the width of the core. 70

4. The combination with a core for forming the opening in the attaching lug of a brake shoe, of a permanent mold for casting the brake shoe and comprising a drag and a two-member cope having a mold cavity therein, each of said cope members having a recess wherein the core may be seated, the recess being of a depth substantially equal to the width of the core, and means for securing to the core the parts which are to be embedded in the shoe casting. 75

5. The combination with a core for forming the opening in the attaching lug of a brake shoe, of a permanent mold for casting the brake shoe and comprising a drag and a two-member cope having a mold cavity therein, said cope members being hinged on the drag member to swing outwardly thereon, each of said cope members having a part of the mold cavity therein and one of said cope members having a recess adapted to receive the entire core. 90

6. The combination with a core for forming the opening in the attaching lug of a brake shoe, of a permanent mold for casting the brake shoe and comprising a drag and a two-member cope having a mold cavity therein, said cope members being hinged on the drag member to swing outwardly thereon, each of said cope members having a part of the mold cavity therein and one of said cope members having a recess adapted to receive and to hold the core in place, the recess being of a depth substantially equal to the width of the core. 100

7. The combination with a core for forming the opening in the attaching lug of a brake shoe, of a permanent mold for casting the brake shoe and comprising a drag and a two-member cope having a mold cavity therein, said cope members being hinged on the drag member to swing outwardly thereon, each of said cope members having a part of the mold cavity therein, and one of said cope members having a recess adapted to receive and to hold the core in place, the recess being of a depth substantially equal to the width of the core, and means for securing to the core the parts which are to be embedded in the shoe casting. 115

8. The combination with a core for forming the opening in the attaching lug of a

brake shoe, of a permanent mold for casting the brake shoe and comprising a drag and a two-member cope having a mold cavity therein, each of said cope members having a part of the mold cavity therein and one of said cope members having a recess communicating with the parting line be-

tween the cope members, the recess being adapted to receive and hold the core in a position wherein one surface of the core is substantially flush with the parting line between the cope members.

JAMES S. THOMPSON.
